US00D807816S

(12) **United States Design Patent** (10) **Patent No.:** **US D807,816 S**
(45) **Date of Patent:** **** Jan. 16, 2018**

(54) **PORTABLE RENEWABLE ENERGY GENERATOR**

(71) Applicant: **Unlimited Power, LTD**, Spindale, NC (US)

(72) Inventor: **Christopher J. Petrella**, Spindale, NC (US)

(73) Assignee: **Unlimited Power, Ltd.**, Spindale, NC (US)

(**) Term: **15 Years**

(21) Appl. No.: **29/579,328**

(22) Filed: **Sep. 29, 2016**

(51) **LOC (11) Cl.** **13-02**

(52) **U.S. Cl.**

USPC **D13/102**

(58) **Field of Classification Search**

USPC D3/201, 218, 219, 269, 272, 273, 274, D3/276, 279, 281, 287, 289, 292, 318, D3/321; D8/375; D9/418; D13/101, D13/102, 103, 106, 107, 108, 110, 116, D13/118, 123, 133, 134, 135, 146, 147, D13/148, 149, 150, 151, 153, 154, 155, D13/156, 159, 161, 173, 184, 199

CPC B64G 1/443; B64G 1/222; Y02E 10/52; H02J 7/355; H02J 17/00; H01M 10/465; H01M 16/006; H04M 19/08; H04M 1/04

(57) **CLAIM**

The ornamental design for a portable renewable energy generator, as shown and described.

DESCRIPTION

FIG. 1 is a perspective view of the portable renewable energy generator;

FIG. 2 is a front view of the portable renewable energy generator;

FIG. 3 is a rear view of the portable renewable energy generator;

FIG. 4 is a left side view of the portable renewable energy generator;

FIG. 5 is a right side view of the portable renewable energy generator; and,

FIG. 6 is a top view of the portable renewable energy generator.

The broken line portion of the figure drawings is included to show portions of the article that form no part of the claimed design.

1 Claim, 3 Drawing Sheets
